TRANSPARENT PACKAGE

Paul J. Fetzek, Toledo, Ohio, assignor to Eltra Corporation, Toledo, Ohio, a corporation of New York
Filed Sept. 26, 1963, Ser. No. 311,754
1 Claim. (Cl. 206—78)

This invention relates to a merchandizing package and more particularly to a method of showing an informative relationship between the merchandizing package and its contents.

The invention contemplates the provision of a transparent plastic package of a type generally referred to as a "bubble" package, which is provided with an informative configuration relative to its end use, for example to indicate the fact that internal combustion engine ignition parts are contained in the package.

The invention provides a package structure for automotive ignition parts having a first transparent outer portion resembling a distributor cap, and a second transparent inner holding portion to cooperate with the first portion to form chambers, both portions being suitably mounted in a cooperative relation on a stiff supporting card.

The invention further contemplates the provision of a transparent package having a suggestive configuration that is related to its contents and which also aids a purchaser by giving him technical information for the use of the contents.

It is, therefore, a principal object of the invention to provide a package having sales appeal for ignition parts which has a suggestive transparent cover formed to resemble a conventional distributor cap.

It is another object of the invention to provide a transparent package of the type described which includes means to retain the ignition parts contained in the package in the same relative position within the package which they have during actual use, so as to indicate to a user the exact positions the parts are to be mounted in the automotive vehicle.

Other objects and advantages of this invention relating to the arrangement, operation and function of the related elements of the structure, to various details of construction, to combinations of parts and to economies of manufacture will be apparent to those skilled in the art upon consideration of the following description and appended claim, reference being had to the accompanying drawings forming a part of this specification wherein like reference characters designate corresponding parts in the several views.

Referring to the drawings:

FIG. 1 is a perspective view showing a transparent package having ignition parts contained therein, a portion of a support member of the package being broken away;

FIG. 2 is a sectional elevation through the package elements showing the assembly of transparent shells and a support member; and

FIG. 3 is a plan view of the support member alone showing an integral flap member.

Referring to the drawings, particularly to FIGS. 1 and 2, a preferred form of a sales package 10 is shown of a type generally referred to as a "bubble" package which consists of transparent shells provided with a suggestive form to indicate the type of merchandise offered for sale in the package. The merchandizing package comprises a transparent outer shell member 12, an inner transparent shell member 14 fitted therein, and a relatively stiff card member 16 which supports the two transparent shell members in their cooperative relation.

The card member 16 is a one-piece member folded over on itself, as shown at 17 (FIG. 2), to provide a double-

2

layer construction having upper and lower plies 16a and 16b. A circular flap member 18 is cut in the card 16 which is hinged to the portion 16a by an integral hinge portion 16c of the card (FIGS. 2 and 3). An aperture 19 is provided at the upper end of the card adjacent the fold 17 to facilitate displaying the package in a handling position.

The cover shell member is generally cup-shaped and also the inner member 14 which have integral outwardly-extending annular flanges 12a and 14a on their lips which overlie each other in superposed relation to provide a means of maintaining the transparent members in assembled relation on the card. As shown in FIG. 2, the transparent members project through an opening 18a in the card (which is provided by forming the flap 18) with the superposed flange portions 12a and 14a bearing against the bottom side of the forward card portion 16a. The lower ply 16b and the flap 18 underlie the flanges to support them in position between the plies of the support member, the flanges 12a and 14a being cut away adjacent the hinge portion 16c to provide the necessary clearance at that point. The package may be maintained in assembled relation, as shown in FIG. 1, in any convenient manner by providing a holding means such as cement, staples, or the like around the edges of the card between the plies to hold the plies together.

An important feature of the invention is the novel method of relating the outer configuration of the package shells to the contents of the package being offered for sale. The package disclosed is designed to contain repair parts for an ignition distributor including a condenser 21, a set of breaker points 23, and a rotor 24. The outer shell member 12 is formed of relatively thin transparent plastic material by a vacuum molding process from a flat sheet of thermoplastic material and is conformed in outline to provide a relationship to the contents, as shown in FIG. 1. A configuration is given to the outer shell 12 resembling that of a typical distributor cap and usually has a plurality of projecting tower portions 12b formed in its upper surface to resemble the towers housing cable-connecting sockets of a typical distributor cap. The member 12 is not a distributor cap but merely a suggestive representation of one for sales appeal. The configuration of the cover thus indicates to a purchaser of repair parts the specific class of merchandise contained in the package (i.e., ignition parts), which also allows visual examination of the contents by a purchaser.

An additional feature in the package is the inner transparent shell member 14 which is mounted in nesting relation with the outer shell 12 to provide a transverse membrane to maintain some of the ignition parts in given positions to suggest the operating relations of the parts in an actual distributor housing. The member 14 is cup-shaped and has a centrally-located depending cup-like cavity 14b formed therein which holds the rotor 24 in a vertical position substantially as shown in FIG. 1. An annular space 14c is formed in the inner shell 14 around the cavity 14b, between the bottom of the shell member 14 and the flap 18 of the holding card which is dimensioned to loosely hold the condenser 21 and the breaker points 23 in the annular space at a level below the rotor to resemble the final position during use. This provides a means for better visual examination of the portions of the various repair parts and also retains the parts in their final mounting positions during use in relation to each other.

The desirable characteristic of the package from a merchandizing standpoint can be further enhanced by providing a printed diagram on the backing member which will inform the purchaser of the exact mounting location or position of the various repair parts within a

distributor housing on the automotive vehicle. This diagram (not shown) may be printed in color with photographic illustrations on the flap 18 of the card 16 and may portray the parts exactly as they would appear in the distributor, the flap being used to represent a distributor plate.

The invention as shown and described is not to be limited to the number of projections 12b on the cover member which in this case represents a six cylinder engine. The same type of package could be used for ignition parts for other engines such as four end eight cylinder engines.

It is to be understood that the above detailed description of the present invention is intended to disclose an embodiment thereof to those skilled in the art, but that the invention is not to be construed as limited in its application to the details of construction and arrangement of parts illustrated in the accompanying drawings since the invention is capable of being practiced and carried out in various ways without departing from the spirit of the invention. The language used in the specification relating to the operation and function of the elements of the invention is employed for purposes of description and not of limitation, and it is not intended to limit the scope of the following claim beyond the requirements of the prior art.

What is claimed:

In a package for merchandising repair parts for an ignition distributor for internal combustion engines comprising an outer inverted cup-shaped transparent plastic cover member, an inner inverted cup-shaped transparent

5 plastic holding member nested within the outer member, the bottom of which forms a transverse wall across the outer member substantially parallel to the bottom thereof, said wall having a central depending well to form a lower annular chamber with the outer member, and a support member for the two transparent members, said transparent 10 cover member having a towered configuration in the bottom of the cup-shape resembling a distributor cap with a distributor cap positioned therein, said transparent cover member and inner member forming at least two superposed chambers including the annular chamber, said chambers retaining a plurality of ignition parts in predetermined positions within the package structure to represent the final operating positions of the various parts.
